D400,870 S * 11/1998 Christensen
D401,921 S * 12/1998 Christensen

* cited by examiner

(75) Inventors: **Parichay Saxena, Milpitas; Sheng Dong, Fremont; Alexandra Nsonwu, San Jose, all of CA (US)**

Primary Examiner—M. H. Tung
(74) Attorney, Agent, or Firm—Skjerven Morrill MacPherson LLP; David W. Heid

(73) Assignees: **Sony Corporation (JP); Sony Electronics, Inc., Park Ridge, NJ (US)**

(57) **CLAIM**

(*) Notice: This patent is subject to a terminal disclaimer.

(**) Term: **14 Years**

(21) Appl. No.: **29/095,446**

DESCRIPTION

(22) Filed: **Oct. 23, 1998**

A portion of the disclosure of this patent document contains material which is subject to copyright protection. The copyright owner has no objection to the facsimile reproduction by anyone of the patent document or patent disclosure, as it appears in the Patent and Trademark Office patent file or records, but otherwise reserves all copyright rights whatsoever.

(51) LOC (7) Cl. **14-02**

The single FIGURE is a front elevational view of a “Spinning Agent” icon for a display screen showing our new design, the broken line disclosure of a portion of a display screen being understood to form no part of the claimed design.

(52) U.S. Cl. **D14/489**

(58) Field of Search D14/114, 114.1-114.9; D18/24-33; D20/11; D19/6; 345/326, 339-40, 347-57; D21/324-33

1 Claim, 1 Drawing Sheet
